(57) **CLAIM**

The ornamental design for a tire fitting machine, as shown and described.

DESCRIPTION

FIG. 1 is a front perspective view of the tire fitting machine;
FIG. 2 is a front view of the tire fitting machine;
FIG. 3 is a back view of the tire fitting machine;
FIG. 4 is a side view of the tire fitting machine;
FIG. 5 is a side view opposite that of FIG. 4 of the tire fitting machine;
FIG. 6 is a top view of the tire fitting machine; and,
FIG. 7 is a bottom view of the tire fitting machine.
